UNITED STATES PATENT OFFICE.

JAMES G. UNDERWOOD, OF SYRACUSE, NEW YORK.

DESIGN FOR A KNITTED FABRIC FOR GARMENTS.

Application filed April 20, 1922. Serial No. 1,903. Term of patent 3½ years.

To all whom it may concern:

Be it known that I, JAMES G. UNDERWOOD, a citizen of the United States, and a resident of Syracuse, in the county of Onondaga and State of New York, have invented and produced a certain new, original, and ornamental Design for a Knitted Fabric for Garments, of which the following is a specification, reference being had to the accompanying drawings, forming part thereof.

The figure represents a small section of the fabric.

The invention comprises a knitted fabric for garments such as is woven on a tricot loom.

I claim:

The ornamental design for a knitted fabric for garments as shown and described.

JAMES G. UNDERWOOD.

Witnesses:

E. E. McDONALD,
NICHOLAS RANSLER.
